UNITED STATES PATENT OFFICE.

FREDERICK H. MILLER, OF WILKINSBURG, PENNSYLVANIA, ASSIGNOR TO WESTINGHOUSE ELECTRIC & MANUFACTURING COMPANY, A CORPORATION OF PENNSYLVANIA.

APPROACH FOR TROLLEY-FROGS.

1,370,033.

Specification of Letters Patent.

Patented Mar. 1, 1921.

Application filed April 9, 1919. Serial No. 288,664.

To all whom it may concern:

Be it known that I, FREDERICK H. MILLER, a citizen of the United States, and a resident of Wilkinsburg, in the county of Allegheny and State of Pennsylvania, have invented a new and useful Improvement in Approaches for Trolley-Frogs, of which the following is a specification.

My invention relates to trolley-conductor devices, such as frogs and crossings, and particularly to renewable approach members therefor.

One object of my invention is to provide a device of the above indicated character that shall be simple and durable in construction, economical to manufacture and effective in operation.

Another object of my invention is to provide a trolley-conductor device that shall comprise only two members at an approach end, which members may be readily placed together in operative position by a simple tool, such as a hammer, and as readily taken apart.

Another object of my invention is to provide an approach member, for a trolley-conductor device, that shall comprise a single integral member having a wedge portion that may be moved relative thereto in mounting the same in operative position.

In practising my invention, I provide a removable extension member for a frog or other trolley-conductor device to take up the shocks and wear incident to the passage of trolley contact members, in which the frog and the extension member are formed and related to permit them to be co-operatively engaged without the aid of any other holding members.

In one form of my device, the approach member comprises an integrally related wedge portion that may be moved relative thereto in securing the same to a frog.

Figure 1 of the accompanying drawings, is an end view of a trolley frog and an approach member embodying my invention; Fig. 2 is a side elevational view of an approach member and one end of the trolley frog shown in Fig. 1; Fig. 3 is a side view, partially in elevation and partially in section, of a modified form of my device; Fig. 4 is a view taken along the line IV-IV of Fig. 3, and Fig. 5 is a side elevational view

of a modified form of approach member embodying my invention.

A frog 1, for the reception of a trolley conductor 2, comprises a channel body member 4 in which the conductor is disposed. An extension or approach member 5, preferably of malleable material, has an inverted channel portion 6 embracing the conductor 2 and a centrally projecting portion or tongue 8 disposed in the channel above the conductor 2. In Figs. 1 and 2, the member 5 is provided with a portion 9 that spans the channel member 4 and has depending portions 10 that embrace outwardly extending projections 11 at the end of the member 4. The projections 11 have sloping surfaces 12 for wedging co-operation with similar surfaces 13 on the portions 10.

In mounting the device, the conductor 2 is placed in the bottom of the channel member 4, the member 5 is placed with its portion 6 over the conductor and is moved toward the member 4 until the surfaces 12 and 13 engage. A few well directed blows against a projection 14 at one end of the member 5 will rigidly secure the member 5 in wedging relation to the frog 1 and the conductor 2.

In Figs. 3 and 4, the wedging surfaces 12 and 13 of the members 4 and 5, respectively, are within the channel, the modification here shown requiring a smaller amount of material but differing in substantially no other respect from the device shown in Figs. 1 and 2.

In Fig. 5, the member 5 has a wedge portion 15 that is connected thereto by a portion 16 of relatively small cross sectional area. The portions 8 and 15 may be cast in spaced relation, as indicated by the dotted-line position of the portion 15, to avoid the requirement of cored holes or machine work, and afterward bent to the relation shown by the full lines. In this form, the member 5 is transportable as a unit and permits a greater range of wedging action, to compensate for possible variations in the co-operating members, by permitting the wedge portion 15 to be moved longitudinally with respect to the tongue 8. This relative movement may be effected by striking the larger end of the wedge portion 15 to stretch or rupture the portion 16.

While I have shown and described particular forms of my invention, changes may be effected therein without departing from the spirit and scope thereof, as set forth in the appended claims.

I claim as my invention:

1. A trolley-conductor device comprising a body member of substantially channel shape for the reception of a conductor and having a longitudinal sloping surface thereon, and an approach member having a co-operating similar sloping surface for wedging engagement with the sloping surface of said body member to rigidly secure both of said members and a conductor in operative relation.
- 10 2. A trolley-conductor device comprising a body member and a single integral approach member coöperating in longitudinally-slidable wedging engagement therewith.
- 15 3. A trolley-conductor device comprising a body member and a single integral approach member coöperating in substantially flat surface wedging engagement therewith.
- 20 4. A trolley-conductor device comprising

a body member and a single integral approach member having relatively movable portions and coöperating in wedging engagement therewith.

30

5. An approach member for a trolley-conductor device comprising relatively-movable integral wedge and body portions for effecting the attachment of said approach member to said device.

35

6. A trolley-conductor device comprising a body member having a wedge receiving portion and an approach member having a yieldable wedge portion permitting the attachment of said approach member to said body member.

40

7. A trolley-conductor device comprising a body member and an approach member for wedging attachment to each other, one of said members comprising integral portions that may be moved relative to each other in effecting said wedging attachment.

45

In testimony whereof, I have hereunto subscribed my name this 2nd day of April, 1919.

FREDERICK H. MILLER.
